UNITED STATES PATENT OFFICE.

ENGELBERT SONTHEIMER, OF NEW YORK, N. Y., ASSIGNOR OF ONE-HALF
TO CORNELIUS BEARD, OF SAME PLACE.

PURSE OR BAG CLASP.

SPECIFICATION forming part of Letters Patent No. 277,064, dated May 8, 1883.

Application filed March 12, 1883. (No model.)

To all whom it may concern:

Be it known that I, ENGELBERT SONTHEIMER, a citizen of Lindau, Kingdom of Bavaria, and a resident of the city, county, and State of New York, have invented a new and useful Improvement in Purse or Bag Clasps or Frames, of which the following is a specification.

The object of this invention is to provide an improved clasp or frame for the mouths of purses, bags, and the like.

The invention consists of a bag clasp or frame the two parts of which are hinged or jointed together with toothed sloping shanked studs in such a manner that suitable pressure on the latter when the bag is closed will effect a downward and unlocking movement of that half of the clasp or frame to which the studs are fixed, so that it may be thrown open by the action of an attached spring; and the invention further consists of novel devices for holding the clasp or frame closed, all of which will be hereinafter set forth.

Reference is to be had to the accompanying drawings, forming part of this specification, in which similar letters of reference indicate corresponding parts in all the figures.

Figure 1 is a plan of my improved device open and attached to a purse or bag. Fig. 2 is a front elevation of the same closed. Fig. 3 represents elevations of the ends of the two sections of the frame or clasp. Fig. 4 is an enlarged side elevation of a stud in position. Fig. 5 is an enlarged side elevation of a portion of the clasp or frame, showing the positions of studs and sections of clasp when pressure is applied to the former for opening the latter. Fig. 6 is an enlarged plan of the same, partly in section. Fig. 7 is an enlarged cross-section of a stud on line xx , Fig. 4.

In the drawings, A A' represent the two sections of my improved clasp or frame applied to a purse or bag, B, in the usual manner of like devices, by rivets $a a$. The enlarged ends of section A have T-shaped slots b formed in them, as shown in Fig. 3, for the accommodation of the studs C C, that pass through them, while the ends of the clasp-section A' have only round perforations c , as shown in Fig. 3, for securely and rigidly hold-

ing the inner ends of the studs C C, that are fixed therein. In assembling the parts of the said clasp or frame the ends of the section A' are placed on the inside of those of section A, the latter section being somewhat larger than the former. 55

Fixed on the inside of the central and highest part of the section A is a downward-projecting locking-pin, d , that engages in the opposite perforated catch, f , of section A' when the clasp is shut, and thereby holds the two sections closed. 60

A spring, D, having its ends fixed to opposing ends of clasp-sections A A', serves to throw and hold said clasp open when it is unlocked. 65

The extremity or inner end of the shank of each stud C is cylindrical, as shown at g , where it passes through the end of clasp-section A', wherein it is held by a burr, h . The remainder of said stud-shank is of parallelogrammic cross-section, about twice as deep as wide, and is inclined upward and outward at an angle of about forty degrees, as shown at i , and on its outer and higher end is formed a head, k . The shank of each stud C has formed 70 on its broadest sides, near its lower end, projecting teeth $m m$, that are designed to engage in the horizontal parts of the slots $b b$ when the clasp or frame is closed, and thereby prevent its becoming opened accidentally by 75 pressure upon the top of the clasp.

When this clasp or frame A A' is closed the flat and inclined shanks of the studs C C rest edgewise in the vertical portions of the T-slots $b b$, and the shank-teeth $m m$ rest in the horizontal portions of said slots, thereby locking the two clasp-sections together. At the same time the pin d engages in the catch f , giving further security to the device. Simple downward pressure applied to the top of the clasp-section A' may release the catch f from the locking-pin d ; but this will not suffice to open the clasp, because the sections A A' cannot turn or move apart so long as the teeth of the studs C C are engaged in the slots $b b$, as above 80 set forth. If, however, the studs C C be pressed inward, as may be readily done between thumb and finger, the teeth $m m$ are thereby disengaged from the slots $b b$, so that the clasp-sections A A' may be moved apart by the action 85 90 95 100

of spring D, and at the same time such inward pressure on the studs C C forces the clasp-section A' downward, because of the inclined planes of the stud-shanks operating against 5 the upper edges of the slots b b sufficiently to release the catch f from the locking-pin d, and then the clasp is thrown open by the spring D.

This device is very simple, effective, and easily applied to purses, bags, and receptacles 10 of like character.

Having thus described my invention, I claim as new and desire to secure by Letters Patent—

1. A purse clasp or frame constructed substantially as herein shown and described, consisting of two clasp or frame sections held or jointed together with studs provided with sloping toothed shanks, all arranged and operating as set forth.

2. In a purse or bag clasp or frame, the combination, with a relatively-fixed section provided with T-slots in its ends, through which actuating studs are passed, of a relatively-movable section in whose ends said studs are fixed, substantially as herein shown and de- 25 scribed.

3. In a purse or bag clasp or frame, studs provided with toothed sloping shanks, substantially as herein shown and described, whereby the clasp or frame may be opened or held closed, as set forth.

4. The combination, with the frame or clasp A A', provided with T-slots b, of the studs C C, constructed with toothed sloping shanks, substantially as herein shown, and for the purposes described.

5. The combination of frame or clasp A A', spring D, studs C C, and pin and catch d f, respectively, all constructed and arranged substantially as herein shown and described.

In testimony that I claim the foregoing as 40 my invention I have signed my name, in presence of two witnesses, this 10th day of March, 1883.

ENGELBERT SONTHEIMER.
